Des. 231,164
Patented Apr. 9, 1974

231,164

MOBILE LOUNGE CHAIR

Thomas Boyd Kellum, 2426 Wild Valley Drive,
Jackson, Miss. 39211

Filed Sept. 5, 1972, Ser. No. 286,093

Term of patent 14 years

Int. Cl. D6—01

U.S. Cl. D6—39

FIG. 1

FIG. 2

FIG. 3

FIG. 1 is a perspective view from a point to the front of a mobile lounge chair, showing my new design;

FIG. 2 is a perspective view from a point to the rear of a mobile lounge chair, showing my new design; and FIG. 3 is a bottom plan view.

I claim:

The ornamental design for a mobile lounge chair, as shown.
